LOOSE LEAF BINDER

John R. Ritzinger, Elizabeth, N. J., assignor to
 Wilson-Jones Company, Chicago, Ill., a corporation of Massachusetts

Application September 10, 1932, Serial No. 632,575

15 Claims. (Cl. 129—13)

This invention relates to a loose leaf binder and more particularly to a binder of the compression type having covers which may be adjusted to accommodate different thicknesses of 5 sheets.

It is an object of this invention to provide a loose leaf binder having a pair of separable back sections that may be easily aligned and compressed to fit the contents of the binder. It 10 is a further object of this invention to provide readily releasable means for preventing accidental separation of the back sections of the loose leaf binder. It is a further object of this invention to provide simple and efficient means 15 for uniting the cover sections and sheet holding prongs to the back section of the binder. Other objects of this invention will become apparent upon reading the following description taken in conjunction with the accompanying drawing in 20 which:

Figure 1 is a perspective view of the binder with parts broken away to facilitate illustration of the structure;

Figure 2 is a plan view of one of the back members and its associated locking slide, with a portion of one end of the back section cut away to facilitate illustration of the structure;

Figure 3 is a front elevation of the structure illustrated in Figure 2;

Figure 4 is an end elevation of the structure illustrated in Figures 2 and 3;

Figure 5 is a fragmentary detail of one end of the other back section;

Figure 6 is a cross section on the line VI—VI 35 of Figure 5;

Figure 7 is a fragmentary detail of one end of the locking slide;

Figure 8 is a cross section on the line VIII—VIII of Figure 7; and

Figure 9 is a detail perspective of one of the sheet holding prongs.

In the drawing the reference numerals 2 and 3 represent a pair of telescoping back sections. The section 2 has its ends bent over as indicated 45 at 4 and 5. The ends 4 and 5 are apertured as indicated at 6 and 7 respectively. The end portions 4 and 5 of the back section 2 are spaced from the body portion of said back section to accommodate a bar or locking slide 8 which is 50 removably secured to said back section 2. These bent over portions 4 and 5 act as retaining flanges in the retention of the slide 8 in desired position. If desired, separate retaining members could be attached to the back member 2 to serve 55 as substitutes for the bent over portions 4 and 5.

As shown in Figure 2, the bar 8 is bowed slightly at its center to provide a space between each end of the bar 8 and the body portion of the back section 2. These spaces 9 and 10 facilitate the positioning of the back section 3 with 60 respect to the back section 2 and the locking bar or slide 8. Either end of the back section 3 may be readily inserted into the desired space 9 or 10, and then the entering longitudinal edge of the back section 3 acts as a wedge which 65 causes the locking bar 8 to yield progressively to permit the proper positioning of the back section 3. The slight bow of the bar 8 which forms the spaces 9 and 10 also makes possible the attainment of other objectives that will be herein- 70 after described.

One end portion 11 of the locking bar or slide 8 is of reduced width so that it may project through the aperture 6 in one end of the back section 2. The width of this portion 11 approximates the width of the aperture 6 sufficiently close to eliminate the possibility of any undesirable lateral motion between the locking slide 8 and the back section 2. The end portion 11 is connected to the main body portion of the slide 8 by means of a tapered portion defined by a pair of shoulders 12. A finger piece 13 for manipulating the slide 8 is formed by bending the end of the reduced end portion 11 at an angle to the body portion of the slide. 75

The opposite end of the locking slide 8 is provided with a reduced portion 14 and a pair of shoulders 15. The end of the reduced portion 14 is bent at an angle to the locking slide 8, as indicated at 16. The height of the bent over portion 16 is approximately equal to the distance between the body portion of the back section 2 and the parallel portion of the turned over portion 5. The slight bow of the locking slide 8 maintains the end 16 in inter-engagement with 90 the aperture 7, as shown in Figure 2. 95

The locking bar or slide 8 is slightly longer than the back section 2 and the shoulders 12 and 15 permit a slight longitudinal movement relative to the back section 2. The end portion 11 of the locking slide 8 is provided with a projection or boss 17 which cooperates with the turned over portion 4 of the back section 2 to maintain the slide 8 in either locking or unlocked position.

The locking slide 8 is of spring steel or similar 105 material, and the slight bow of the slide 8 hereinbefore mentioned is sufficient to maintain the end portion 11 of the slide in constant contact with the turned up portion 4 of the back section 2. Accordingly, the projection 17 will prevent 110

accidental movement of the slide in either direction, because each time such movement takes place the slide 8 must be depressed slightly to permit the projection 17 to pass under the edge of 5 the turned over portion 4 of the back section 2. The locking bar or slide 8 may be easily removed from the back section 2 by pressing the end 16 down and moving it laterally from out of contact with the turned over portion 5.

10 The locking slide 8 is provided with a projection 18 at each end thereof. The back section 3 is provided with a plurality of projections 19 adapted to cooperate with the projections 18 to maintain the back section 3 in position. These 15 projections are shown as being struck out from the metal of the slide and back section, and this method of formation is preferred because of its simplicity and economy. However, the projections could be formed in any simple manner as 20 by embossing or crimping the metal, or by riveting or welding preformed strips of suitable shape to the slide 8 or back section 3. If desired, the slide 8 may be provided with an aperture and a spring pressed tooth extending through the aperture to engage the projections 19 on the back section 3. It is also possible if desired to substitute a plurality of projections for the single projection 18 at each end of the slide. However, it has been found that a single projection 18 is 25 sufficient to maintain the units of the binder in position under extremely unfavorable conditions.

The longitudinal displacement permitted for the slide 8 is sufficient to allow the projection 18 to be moved entirely out of interlocking engagement with the projections 19. The back of the binder may be closed by moving the slide 8 into locking position and then compressing the back sections 2 and 3, or by compressing the back sections as far as possible when the slide 8 is in 40 unlocked position and then moving the slide 8 to engage the projection 18 with one of the series of projections 19.

The projections 19 are preferably formed to extend at an angle of approximately 10 degrees to 45 the longitudinal edges of the back section 3. When the back sections are compressed before the slide 8 is moved to locking position, the projections 19 because of the angle at which they extend, act as cams to guide the back sections 50 into closer relationship so as to compress the sheets to a greater extent than if the projections were parallel to the longitudinal edges of the back sections. It is preferred to form the projection 18 at an angle, as shown in Figure 7, to 55 increase the strength of the inter-engagement between the projections 18 and 19, but this is not essential, and the projection 18 may be formed of any desired shape. The inter-engagement of the projections 18 and 19 effectively prohibits the 60 accidental separation of the back section 3 and the locking bar or slide 8.

Each back section has one longitudinal edge bent to form a double walled side member 20. Since both the side members are duplicates of 65 each other, only one need be described. The side member 20 is provided with one or more apertures 21 at its apex. A prong member 22 is positioned so that its tine 23 projects through said aperture and its base portion 24 is retained between the two walls of the side member 20. The 70 cover member 25 has one edge positioned between the two walls of the side member 20, and then these side walls are clinched together to secure the cover member and the prong member permanently in position.

It is obvious that the prong members 22 could be secured to the back section in any suitable manner, but the method described is preferred because of its simplicity and efficacy. The prong 80 22 may be of any suitable shape, but the flat prongs shown are preferred because this type of prong permits the sheet 26 to lie flat when the book is open, without any appreciable waste at the inner margin of the sheet.

The assembly of the various elements of the binder is extremely simple. After the double walls constituting the side members have been clinched together to secure the cover members and prongs in place, the finger piece 13 of the locking bar or slide 8 is pushed through the aperture 6 and then the slide 8 is pivoted to bring it in a plane parallel to the back section 2. The slide 8 is then moved laterally until the turned up portion 16 is under the aperture 7. When the slide is released its spring action forces the portion 16 into engagement with the edges of the aperture 7. The sheets 26 are impaled on the tines 23 of the prong members 22. One end of the back section 3 is then inserted into either space 9 or 10, and then the rest of the back section 3 is positioned as the slide 8 progressively yields to the entering edge of the back section 3.

The inter-engagement of the projections 18 and 19 prevents the lateral separation of the back sections 2 and 3. When it is desired to remove 105 or add a sheet to the binder, the finger piece 13 is manipulated so as to move the projection 18 out of engagement with the projections 19 so as to permit separation of the back section 3 from the binder. The projection 18 may be moved 110 into its locking position either before or after the back section 3 is reinserted in position. When the back section 3 is reinserted in position before the slide is moved so as to bring the projection 18 into its locking position the full benefit of 115 the cam shape of the projections 19 is attained. The peculiar arrangement of the projections 19 effects a guiding action on the projection 18 so as to facilitate the operative inter-engagement of the projections. It will be seen that the projection 18 can engage with any of the projections 19 depending upon the thickness of the body portion of paper in the binder.

While I have described a preferred embodiment 125 of my invention in detail, it will be understood that the description thereof is illustrative rather than restrictive as many details may be modified or changed without departing from the spirit or scope of the invention. Accordingly, I do not desire to be restricted to the exact construction 130 described except as limited by the appended claims.

I claim:

1. In a loose leaf binder, a back section, a locking slide removably secured to said back section, a second back section, and means to secure said second back section between said first mentioned back section and said locking slide in a plurality of positions.
2. In a loose leaf binder, a back section, said 140 back section having a double bend at its outer edge to provide a relatively low, double walled side member, a prong member having a tine projecting through an aperture formed at the apex of said side member, and a cover having one 145 edge positioned between the walls of said side member, said side member being adapted to have its walls clinched together whereby said prong member and said cover member are rigidly secured in position.

3. In a loose leaf binder, a back section, a plurality of retaining flanges on said back section, a locking slide retained in position by said flanges, a second back section, and means to secure said second back section between said first mentioned back section and said locking slide in a plurality of positions. 80
4. In a loose leaf binder, a back section, a locking slide, means on said back section for holding said locking slide in position, a second back section, and means to secure said second back section between said first mentioned back section and said locking slide in a plurality of positions. 85
5. In a loose leaf binder, a back section having apertured, turned over end portions spaced from the body portion of said back section, a bar having its ends extending through said apertured end portions, the ends of said bar extending at an angle to its body portion whereby said bar is maintained in position, and a second back section adapted to be positioned between said bar and said first mentioned back section. 90
6. In a loose leaf binder, a back section, a bar removably secured to said back section, a projection on said bar, a second back section adapted to be positioned between said bar and said first mentioned back section, and a plurality of cam shaped projections on said second mentioned back section arranged to cooperate with said first mentioned projection to guide said bar into interlocking engagement with said second mentioned back section and to increase the compression between said back sections. 95
7. In a loose leaf binder, a pair of back sections, and a locking slide, said locking slide being bowed at its center and having its ends spaced slightly from the ends of one of said back sections, whereby said other back section may be readily positioned between said locking slide and said first mentioned back section. 100
8. In a loose leaf binder, a back section having its ends bent to form retaining flanges, a bowed locking slide having its ends bent at right angles and retained by said retaining flanges, and a projection on said locking slide adapted to cooperate with one of said retaining flanges to prevent accidental longitudinal movement of said locking slide. 105
9. In a loose leaf binder, a back section, a slideable bar removably secured to said back section, means on said back section to limit longitudinal movement of said bar, a second back section adapted to be positioned between said first mentioned back section and said bar, a plurality of projections on said second mentioned back section, and a projection on said bar movable into and out of interlocking engagement with said 110
- projections on said second mentioned back section, whereby said second mentioned back section may be held in, or released from, operative relationship with said first mentioned back section. 115
10. In a loose leaf binder, a back section having a plurality of parallel projections struck out from the body of said back section, a second back section, a locking slide removably secured to said second back section, and a projection on said locking slide adapted to inter-engage with said projections on said first mentioned back section. 120
11. In a loose leaf binder, a pair of back sections, a locking slide removably secured to one of said back sections, a series of cam shaped projections struck out from the body of said other back section, and a projection on said locking slide adapted to be moved into and out of engagement with said projections on said second mentioned back section. 125
12. In a loose leaf binder, a back section having flanges at its opposite ends, a bar having its ends retained by said flanges, said bar having means at one end thereof for moving said bar longitudinally with respect to said back section, and means to prevent accidental longitudinal movement of said bar. 130
13. In a loose leaf binder, a back section having flanges at its opposite ends, a bowed bar having its ends retained by said flanges, said bar being movable longitudinally with respect to said back section, and means on said bar adapted to cooperate with one of said flanges to prevent accidental longitudinal movement of said bar. 135
14. In a loose leaf binder, a three unit back construction including two back sections and a locking slide, one of said back sections having means to removably secure said locking slide thereto, said back sections being capable of lateral expansion within a substantial range without disassociation, said locking slide and said second back section having cooperating means to secure said second back section against expansion between said locking slide and said first mentioned back section at any point within said range of lateral expansion. 140
15. In a loose leaf binder, a three unit back construction including two telescoping back sections and a locking slide, one of said back sections having means to removably secure said locking slide thereto, said locking slide and said other back section having cooperating means to secure said other back section in position between said locking slide and said first mentioned back section, said other back section retaining its position between the first mentioned back section and the locking slide during expansion of the binder. 145
